UNITED STATES PATENT OFFICE.

JOHN T. HAEUSSER, OF ALBANY, NEW YORK.

TUBULAR BOILER.

1,186,573.

Specification of Letters Patent. Patented June 13, 1916.

Application filed July 10, 1915. Serial No. 39,058.

To all whom it may concern:

Be it known that I, JOHN T. HAEUSSER, a citizen of the United States of America, residing in the city of Albany, in the county 5 of Albany and State of New York, have invented certain new and useful Improvements in Tubular Boilers, of which the following is a specification.

My invention relates to tubular boilers, 10 and the object of my invention is to provide a metallic conductor adapted to be inserted in tubes; together with such other elements and combinations as are hereinafter more particularly set forth and claimed. I accomplish 15 these objects by means of the mechanism illustrated in the accompanying drawing, in which:

Figure 1 is a cross section along the lines, 1—1, on Fig. 2. Fig. 2 is a longitudinal section of a boiler tube with my conductor placed therein. Fig. 3 is a section of a furnace with a tubular boiler placed therein, with parts of the boiler broken away, showing the tubes with my conductor placed 25 therein.

Similar letters refer to similar parts throughout the several views.

The boiler, C, is provided with a series of tubes, B, in the usual manner, through which 30 the heat and gases of combustion pass, as indicated by the arrows, from the furnace, D, in the usual manner.

When the furnace is in operation the most intense heat conducted through each tube 35 will be along its central line, that is, it is hotter midway between the sides of the tube than it is at the sides of the tube. A core of intense heat, so to speak, is formed along the central longitudinal line of the tube. In 40 order that the heat thus formed may be conducted to the walls of the tube, I place a metallic conductor, A, into the tube extending as far as desired. The metallic conductor, A, is preferably bent so that two of its 45 sides will approach each other, making the space between the two sides, a, b, such that they will come into contact with the hottest

part of the stream or current of heat passing through the tube, B. Becoming very hot from its close association with the super-heated portion, it will conduct the heat and bring it into contact with the walls of the tube, B, where the sides of the conductor, A, contact therewith as at f, g.

I make a series of holes, E, along the sides, 55 a, b, of the conductor, A, which will tend to equalize the pressure of the burning gases on the sides of the conductor, and into the holes nearest the end a hook, not shown, may be inserted for withdrawing the conductor 60 from the tube.

The conductors, A, may be easily inserted into the tubes or removed therefrom when desired, their flexibility permitting of their being thus easily placed in position.

My invention may be used for cooling as well as heating, for when it is desired to conduct the heat from the walls of a tube toward the center, thus coming in contact with air passing therethrough, the heat will be conducted from the walls, resulting in cooling 70 them.

I do not limit myself to the construction of the boiler as shown, nor to the conductor formed as illustrated.

What I claim as my invention and desire to secure by Letters Patent is:

A metallic conductor adapted to be inserted into a tube, comprising a flexible metallic tube with two of its sides bent toward 80 each other and a series of holes along said bent sides, the other two sides adapted to engage the sides of the tube, forming a straight contracted longitudinal passageway through the conductor and enlarged uninterrupted 85 longitudinal passageways in proximity to the sides of the boiler tube, substantially as described.

In testimony whereof I have affixed my signature in presence of two witnesses.

JOHN T. HAEUSSER.

Witnesses:

BEULAH CARLE,
FREDERICK W. CAMERON.
